UNITED STATES PATENT OFFICE.

CARL F. WILSON, OF BAY CITY, MICHIGAN.

WALKING-MACHINE.

1,267,033.

Specification of Letters Patent. Patented May 21, 1918.

Application filed July 1, 1916. Serial No. 107,159.

To all whom it may concern:

Be it known that I, CARL F. WILSON, a citizen of the United States of America, residing at Bay City, in the county of Bay and 5 State of Michigan, have invented certain new and useful Improvements in Walking-Machines, of which the following is a specification.

This invention relates to a movable supporting device especially adapted for carrying and moving dredges or the like from one position to another by a series of steps in such manner that the dredge or other similar machine may progress with the work 10 that is being accomplished by it. Heretofore in moving machines of this character it has been necessary to lay a track for the supporting frame on which the working machine is mounted, a great deal of time and 15 labor and expense being consequent to the track laying. My invention has for its primary object and purpose the provision of a simple mechanism whereby this expense may be eliminated, no bed or track for transporting the machine being necessary. Other 20 objects and purposes together with novel and useful construction for attaining the same will appear as understanding of the invention is had, reference being made to the action 25 accompanying drawings, in which;

Figure 1 is a plan view of the movable support for the dredge or like machine.

Fig. 2 is a side elevation thereof.

Fig. 3 is a view similar to Fig. 2 showing 35 a different position of the parts during the movement thereof.

Fig. 4 is another view similar to Figs. 2 and 3 illustrating a still further position of the parts during their operation.

Fig. 5 is a vertical section upon the line 40 5-5 of Fig. 3; and

Fig. 6 is a plan view showing the pivotal connection of one of the moving parts of the machine whereby its direction of movement may be changed.

Like reference characters refer to like parts throughout the several views of the drawings.

In the preferred embodiment of my invention as disclosed in the drawings, spaced apart runners 1 are provided formed preferably of channel iron and having their forward ends turned upwardly as shown at 2, each of these runners for the major part of 55 its length being reinforced by a centrally

located I-beam 3. At each end of each I-beam a bracket 4 is mounted, each pair of brackets carried by an I-beam serving to support the ends of I-beams 5. The frame is completed by cross beams 6 of any preferred type and braces 7 which lead from the forward ends of beams 5 to the forward ends of the runners 1. This frame may carry any suitable mechanism such as needs to be moved intermittently with the progress 60 of the work done by such mechanism such for instance, as a dredge, the boom of which may be mounted on the forward beams 6, it however, forming no part of the present invention. 65

Adjacent the rear end of the frame a knuckle 8 is mounted upon a shaft 9 at each side of the frame, this knuckle being of the ordinary and well known type of steering knuckle used in self-propelled vehicles and 70 having a spindle 10 on which is mounted a roller 11 provided with a central flange 12, the knuckle also having an arm 13 positioned substantially at right angles to the spindle 10. The ends of arms 13 are connected by 75 rods 14 which at their center carry a short rack 15 with which a pinion 16 on a steering post or rod 17 engages. The runners 1 lie upon the ground, the outer surface of the rollers 11 being substantially in the same 80 plane at their lowest points with the undersurface of the runners while the central rib or flange 12 embeds itself in the ground.

Near the forward end of the frame a cross shaft 18 is mounted in bearings 19. At each 90 end of the shaft a loose sleeve 20 is mounted being retained thereon by a collar 20a. A gear 21 is keyed or in any other suitable manner permanently secured to the sleeve 20 while alongside of this gear a 95 segmental gear 22 is also permanently secured to the sleeve. The segment of the gear 22 is housed within a member comprised of upper and lower channels 23 and 24 connected at their ends by integral curved channels 25. On the underside of the upper channel 23 a rack 26 is formed and similarly on the upper side of the under channel 24 a rack 27 is formed. An elongated block 28 is pivotally connected beneath the under channel portion 24, it lying between the upwardly extending flanges of an auxiliary runner 30, the front end of which is turned upwardly at 31 to correspond with the front end 2 of the main run- 100 105 110

ner 1. Roller bearings 32 are provided between the upper face of the block 28 and the underside of the under channel 24.

Meshing with gears 21 are pinions 33 mounted at the outer ends of shafts 34 which are carried in bearings 35 back of and connected to the upper side of the I-beams 5. Interposed between shafts 34 is a shaft 36 on which is mounted a sprocket wheel 37 which may be continuously driven from any suitable source of power. Friction clutches 38 between the ends of shaft 36 and each of the shafts 34 are used to connect the shaft 36 with either or both of the shafts 34 at will.

When it is desired to move this frame ahead in a straight line both of the clutches 38 are operated so that both of shafts 34 are driven these, in turn through gears 33 and 21 simultaneously, turning the segmental gears 22 about shaft 18. The gear segments first engage with the lower rack 27 elevating the forward ends of runners 1 and as the turning movement of the segmental gears progresses carrying said runners and attached parts forward until the segmental gears 22 disengages from the lower rack. When this disengagement takes place the auxiliary runners 30 are positioned to the rear with respect to the main runners 1 and as the continuation of the movement of the segmental gears continues so that they engage with rack 26, the auxiliary runners and the housing formed of channel iron members are elevated, these auxiliary runners in turn being carried forward, it being apparent that during this movement, by reason of the over-balancing of the rear end of auxiliary runners, the forward ends are elevated farther above the ground so as to be clear of any obstacles to their movement. As long as the clutches 38 remain in engagement, this step by step movement continues and the frame is carried forward in a straight line by a series of steps which may be discontinued at any time by operating clutches 38 to disconnect the power.

When a change of direction is desired steering rod 17 is turned so that the wheels 11 are positioned at an angle as indicated in dotted lines in Fig. 1. One only of the clutches 38 is then operated to connect one of the shafts 34 with the power shaft 36, causing a forward movement of one side of the machine and a turning of the entire machine on the opposite auxiliary runner about the pivot 29. Of course during this operation of turning it is necessary to guard against sharp angles of turning and the operator, while one clutch 38 remains continually in operative position, intermittently works the other clutch 38 to operate its associated segmental gear 22 sufficiently that the auxiliary runner 30 associated with that gear does not become turned so that the rollers 32 come out from under the channel 24.

With a device of this character heavy machinery may be moved without the necessity of laying tracks for its support and this upon comparatively soft ground by reason of the wide bearing surface of the main auxiliary runners. Many changes in constructive detail for attaining the result described may be resorted to without departing from the invention defined in the appended claims and accordingly I consider myself entitled to all modifications of structure falling within the scope of the claims.

I claim:—

1. A traveling frame, comprising main and auxiliary supports adapted to be intermittently lifted and moved forward, a segment mounted upon one of the supports and adapted to have a rotary movement imparted thereto, and upper and lower racks mounted upon the remaining support and adapted to be alternately engaged by the segment gear.

2. A traveling frame, comprising main and auxiliary runners adapted to be alternately lifted and moved forward, upper and lower racks mounted upon the auxiliary runner and having pivotal connection therewith, and a segment gear rotatably mounted upon the main runner and adapted to engage the racks in alternation.

3. In a device of the character described, a frame including spaced apart main runners, a shaft on the frame, a segmental gear loosely mounted at each end of the shaft, an auxiliary runner located at each end of the shaft, a housing connected to and above each auxiliary runner in which the segmental gears are located, upper and lower racks in each housing for engagement by said segmental gears, and means to drive the gears, substantially as described.

4. In a device of the character described, a frame including spaced apart main runners, a shaft on the frame, a segmental gear loosely mounted at each end of the shaft, an auxiliary runner located at each end of the shaft, a housing pivotally connected to and above each auxiliary runner in which the segmental gears are located, upper and lower racks in each housing for engagement by said segmental gears, and means to drive the gears either separately or in unison, substantially as described.

5. In a supporting frame for dredges or the like, spaced apart main supporting runners having a comparatively wide under surface, a reinforcing beam extending from the rear end of each runner part of the length of said runner, brackets on the beams, a longitudinal beam carried by said brackets, and cross beams interposed between the longitudinal beams, said forward cross beams being located a distance back of the front ends of the runners whereby a dredge or the like mounted on the frame is held

from over-balancing toward the front by the forward extensions to the runners in front of the forward cross beams, substantially as described.

- 5 6. In a device of the character described, a frame including spaced apart main supporting runners, a shaft on the frame, a sleeve loosely mounted at each end of the shaft, a gear and a segment of a gear fixed
- 10 to each sleeve, a housing comprised of upper and lower channel members connected together in spaced apart relation at the ends thereof in which each segmental gear is located, upper and lower racks in the housing,
- 15 an auxiliary runner attached to the under-side of each housing, a pinion meshing with

each gear, a shaft for each pinion mounted on the frame, and means for driving said shafts either separately or in unison.

7. A traveling frame, comprising main 20 and auxiliary runners adapted to be alternately lifted and moved forward, segment gears independently mounted upon the main runners and adapted to be rotated at the same or different speeds, and upper and 25 lower racks mounted upon each of the auxiliary runners and having pivotal connection therewith and adapted to be engaged in alternation by the coöperating segment gears.

In testimony whereof I affix my signature.
CARL F. WILSON.
